UNITED STATES PATENT OFFICE.

JOHN F. AMES, OF PORTLAND, OREGON.

BAG-MAKING MACHINE.

SPECIFICATION forming part of Letters Patent No. 709,451, dated September 16, 1902.

Application filed February 28, 1900. Serial No. 6,827. (No model.)

To all whom it may concern:

Be it known that I, JOHN F. AMES, a citizen of the United States, residing in Portland, county of Multnomah, State of Oregon, have ⁵ invented an Improvement in Bag-Making Machines; and I hereby declare the following to be a full, clear, and exact description of the same.

My invention relates to a machine for making bags complete from cloth which is furnished in continuous rolls or lengths of any desired quantity. The machine or apparatus includes means for feeding the cloth from a continuous roll and advancing it through the machine, first, to a cutter by which it is cut to a desired length to make the desired size of bag; secondly, to a folder by which the separated sheet is folded centrally, so as to bring the edges together. The folded sheet ¹⁵ is then advanced to a sewing-machine, which sews one end. It is then advanced to a point where its direction of motion is changed, and it is moved transversely and at right angles with its former direction, thus passing the edges of the folded sheet through another machine, which sews up this edge. The bag is ²⁰ thus completed with one side formed by the fold, the bottom sewed across by the first machine, and the sides sewed up by the second machine as the bag moves transversely ²⁵ through it. Bags thus completed are discharged at the end of the machine and have the advantage of being formed with a finished selvage at the open mouth. My invention ³⁰ also comprises details of construction by which this operation is carried out.

Referring to the accompanying drawings, Figures 1^a and 1^b, Sheets 1 and 2, are a plan view of the machine. Fig. 2 is an elevation ⁴⁰ of the cloth-supply device. Fig. 3 is a detail of the device for operating the shears. Figs. 4^a, 4^b, and 4^c, Sheets 3, 4, and 5, are the front elevation of the machine. Fig. 5 is a vertical section through the cloth-feeding device. Fig. 6 is a top view of the rollers used in the folding device. Fig. 7 is an elevation of that ⁴⁵ part of the machine which extends at right angles from the extreme right of the machine. Fig. 8 shows a modification of the cloth-feed. ⁵⁰ The object of my invention is to form complete bags having a finished selvage around the mouth, said bags being formed continu-

ously from cloth which is supplied in any desired lengths and from which the bag is completed in a single continuous operation. ⁵⁵

Various modifications of the mechanism which I have here shown may be made without materially altering the essential features of the work, such mechanism being common expedients and well-known mechanical equivalents.

In the present case I have shown the machinery necessary to carry out my invention mounted upon a main framework A of any suitable description. ⁶⁵

Power to drive the various mechanism is derived from a belt, chain, or other driver 2, passing around a pulley or sprocket-wheel 3, and upon the shaft of this pulley is mounted a pinion 4, the teeth of which engage the corresponding teeth of a gear-wheel 5, thus transmitting power to it. Upon this shaft and preferably at each side of the machine are mounted disks 6, which are turnable in unison with the shaft. These disks are slotted radially, as shown at 7, and crank-pins 8 are mounted upon blocks or carriers slideable in these slots, and they are adjusted to or from the center by screws 9 or equivalent devices. From the crank-pins 8 pitmen or connecting-rods 10 extend and connect with sliding rods 11. These rods travel through guides 12, arranged along the sides of the machine at suitable intervals, and they carry various mechanisms by which the operations of forming the bag are produced. The sliding rod is an important feature of the machine. It operates the lever which works the knife to cut the cloth, the lever which operates the folding mechanism, the lever which actuates the twine-cutter between the bags after the ends are sewed, the roll that changes the movement of the bags and passes them to the second sewing-machine, where the sides are sewed, and the final cutter for severing the thread after the bag is completed. ⁸⁵

The cloth from which the bags are to be made will be of sufficient width to make the length of a bag, (and as it is woven with selvages upon the sides there will be no raw edges at the open end of the bag,) which is important, and especially in larger sizes of bags. This cloth may be brought to the apparatus from any suitable source of supply ¹⁰⁰

and in any convenient or suitable manner. In the present case I have shown the cloth B as mounted upon large rolls, as shown at 13, and these rolls may carry a thousand or fifteen hundred yards or more, if desired. Power to rotate the roll is derived through mechanism intermediate between the roll and the main driver. As here shown, a belt 14 passes from a pulley 15 on the shaft of the gear 5 to a pulley 16, and from a pulley driven by 16 a belt passes to another pulley 17, between which and the cloth-roll is a small pulley 18, mounted upon a shifting arm 19, suitably pivoted or supported so that the pulley 18 may be interposed between 17 and 13, if desired. By means of this pulley the movement of the cloth-roll can be reversed at pleasure. As at present shown, the cloth from the roll passes through suitable guides 20 and tension devices, as shown at 20. Thence it passes up between rolls 21 and 22, which act as feeders to advance the cloth which is pressed between them. The connecting-rod of pitman 10, previously described, acts to reciprocate a rack-bar 23, which is moved in unison with the sliding rod 11. The teeth of this rack-bar engage the teeth of a pinion 24, and upon the shaft with this pinion is mounted a ratchet-wheel 25. A pawl 26, carried by the gear-shaft, engages the teeth of the ratchet-wheel 25 when upon a forward movement of the rack-bar and rotates the ratchet-wheel and the drum or roller 22, the relation, arrangement, and proportions of the parts being such that the cloth is advanced between these rollers a distance equal to twice the stroke of the rack-bar. The length of this stroke is regulated to suit the size of bag to be made by the movable crank-pin 8 and the adjusting-screw 9, by which the radius and throw of the crank are changed as the cloth is thus moved forward between the rolls on the forward motion of the crank and rack-bar and remain stationary on the reverse or backward movement. This shows one means for intermittently advancing the cloth. Another form is shown in Fig. 8, in which a sprocket-wheel is substituted for the gear 24, and a sprocket-chain connecting with a sliding frame *a* passes over the sprocket-wheel and hanging down has a weight *d* at its lower end, which thus keeps the chain engaged with the teeth of the sprocket. The forward movement of the sliding frame, which is the equivalent of the rack-bar 23, then acts to rotate the sprocket-wheel by pulling on the chain, and thus acts through the ratchet-wheel 25 and pawl 26, as previously described. The weight *d* will revolve the sprocket-wheel in the opposite direction upon the return movement of the crank and pitman in the same manner that the gear-wheel 24 is acted upon. Other equivalent devices may be employed for producing the necessary reciprocation; but these fairly illustrate the operation.

The upper roll 21 has its journal-shaft sup-

ported by a frame 27, which is pivoted, as shown at 28.

29 is a belt which passes around the rollers 70 or drums 22, 30, 31, 32, 33, and 34, and this belt serves to support the cloth after it leaves the drums 21 and 22. The rollers 32 and 34 are sufficiently separated to allow the knife 35 to reciprocate vertically between them, and 75 the roller 33 is situated sufficiently lower than these two to carry the belt 29 down below the lowest point to which the knife or cutter moves, thus protecting this carrying-belt from being cut by the knife. Various 80 forms of cutter may be employed. In the present case I have shown an upper movable cutter 35 and a lower stationary cutter over which the cloth passes between the rollers 32 and 34. The upper knife is pivoted at one 85 end, and at the opposite end is operated by a lever-arm 36, which is pivoted, as shown at 37.

38 is an inclined surface carried by the sliding rod 11 in its reciprocations, and this incline on its backward movement engages a pin 39 on the end of the lever 36 which is opposite to the connection with the knife 35. The action of this incline forces the knife-blade down and severs the cloth at this point, 95 while it remains stationary during its intermittent movement. As soon as the sliding rod moves forward and carries the incline 38 out of engagement of the pin a spring 40 acts to return the knife to its position, and when 100 the cloth is again advanced it passes from the roll 34 to the roll 32, and the corresponding pressure-rollers 41 above acting with 32 and 34 continue to advance the cloth beyond this point. After leaving the cutter the cloth 105 passes between the rollers 31 and 42, which continue to advance it, and thence over the roller 43. Between the rollers 31 and 43 are situated two small rollers 44 and 45. The cloth after being severed by the cutter is carried along by the next reciprocation, so that 110 its center is exactly in line beneath the folding-blade 46, which is operated by lever-arms 47. These lever-arms are fulcrumed, as shown at 48, and have pins 49, which are engaged 115 by the inclines 50, carried by the sliding rod 11 and acting upon the pins 49 to tilt the levers 47 in the same manner as described for actuating the cutter, except that in this case both ends of the folder are moved down simultaneously, and the blade striking the cloth forces its bight down between the rollers 44 and 45, thus folding the cloth exactly in the middle. The folder is returned after the pin 49 is released from the incline 50 by a spring 120 or springs 51, and this leaves the way clear for the cloth to be again advanced on the forward motion of the stroke. Since the roll 42 rests upon the cloth, it is necessary to raise it at the instant when the folding-blade is 125 pressed down to pass the fold of the cloth between the rolls 44 and 45. This is effected by levers 52, fulcrumed, as shown, at 53 and carrying the journal-box of the roll 42 at one 130

end and having the other end connected with the lever 47, as shown at 54, so that when this lever is moved to depress the folder the first action will be to lift the roll 42 and allow the length of cloth from which the bag is to be made to be freely advanced from the rear, while the portion which has passed the folder will be equally drawn backward, so that when the fold is complete the two edges of the cloth will be brought together ready for stitching. In order to keep the roll 42 raised until the cloth has been entirely withdrawn from between 42 and 31 by the action of the folding-rolls 44 and 45 the incline 50, which first acts to raise the roll and to depress the folder, is continued in an approximately horizontal plane, so that the parts are held in this position until the return movement of the stroke has been very nearly completed, when the incline 50, arriving beneath the pin 49, will allow the parts to resume their normal position.

In order to prevent the cloth from being cut by too great pressure in case it is creased or to allow it to pass between the rollers 44 and 45 if any thickening of the cloth takes place, I have shown the roller 45 mounted in a movable bearing. This movable bearing in the present case is carried by the levers *c*, pivoted at *d* just below the roll, and by means of a spring *f* sufficient pressure is brought upon the lever to hold the roller 45 very firmly against 44, but yet allowing it to yield, so that if the bag *C* became creased it would pass between the rolls without being cut. The folded cloth now passes down and is delivered to pass beneath a roller 55, around which pass the belts or tapes 56. Below this roller is another continuously-traveling belt 57, and the folded bag *C* passes between the tapes 56 and the belt 57. This holds the bag *C* in proper position until it is again brought up to the level of the main frame, along which it is then carried to the first sewing-machine, which is indicated at 58. The belts 56 and 57 pass around and over suitable guide and direction rollers. The upper belt is shown as passing from the roller 55 over the roller 59, thence along the level, passing the sewing-machine 58, thence around the roller 60, thence over the adjustable tension-roller 61, thence returning to roller 55. Belt 57 passes in unison with the belt 55 over the roller 59, thence to the rear end of the machine over a roller 62, thence returning to a direction-roller 63, thence passing around guide-rollers 64, which return it to again coincide with the belt 56, passing around the roller 55. When the folded bag *C* reaches the first sewing-machine 58, being carried along between the belts 56 and 57, the folded edge, which is to form the bottom of the bag, passes through the sewing-machine, so that the reciprocation of the needle will sew this edge as it passes. The proportionate speed of the parts is such as to maintain a slight forward tension upon the material. Any suitable form or arrangement of

sewing-machine may be employed. I have only indicated the position of a machine and mechanism by which it may be driven, which is here illustrated by the pulleys 65 and 66 and the belt 67. Power is here shown to drive the pulley 65 by means of beveled gear 68; but any other suitable mechanism may be substituted or employed for the purpose. Emerging from the sewing-machine at 58 the bag next passes beneath the roller 60, and a thread-cutter at 69 serves to sever the thread by which the bottom of the bag had been sewed. The bag then passes on and between the rollers 70 and 71, which continue to advance it until it strikes a stop 72. At this point the motion is changed and the bag is moved at right angles with its previous movement by means of a roll 73. After leaving the rolls at 60 and the blades of the shears which cut the thread between the bags the bag passes between the two rolls 70 and 71, which move more rapidly than the belts, and the bag is thus carried forward to the stop 72, which limits its motion in that direction. At this instant the roll 73 is raised by the action of the sliding rod 11, which in its reciprocations causes a block 77 to act upon an arm 79 on a rod 80', which carries the levers 74, in the ends of which the roller 73 is mounted. As soon as the bag has reached the stop 72 the roller 73 is lowered, and, pressing upon the bag, motion communicated to rotate this roller causes the bag to be moved at right angles with its former movement. This movement of the bag carries it beneath the second sewing-machine, which is indicated at 76, and the unfinished edge, which is the one formed by the previous folding of the bag and bringing the two edges together, is then sewed by this machine. The movement of the transverse belts 78, which carry this bag, is so regulated that the rear end of the latter passes sufficiently forward to permit the next bag to pass without interference when it is advanced to the stop 72. After passing the second sewing-machine the twine or thread by which the bag was sewed is cut by a mechanism similar to that described at 69, and the bag is then ready to be discharged. The mechanism for actuating the shears 69 is operated as follows: A block 77 is carried by the sliding rod. The upper part of this block carries a divergent plate, and this plate acts when the rod moves in one direction to tilt a lever-arm 79, this arm being mounted upon a pivot-shaft 80. Another arm of the pivot-shaft projects in such a way that it acts upon the shears 69 when the divergent plate 77 tilts the lever and closes the shears to cut the thread. As soon as the plate 77 has passed the arm 79 the latter, acted upon by a spring, returns behind the end of the plate 77, thus allowing the shears to open. As the rod 11 again advances it is necessary to allow the plate 77 to pass 79, and this is effected by jointing the upper end of the arm 79 and pivoting this jointed portion, which is represented

at 81, so that it will yield, tilting in the line of movement of the rod 11 or block 77, so that it passes beneath the plate, until the narrower portion of the plate comes in line with it, 5 when the part 81 will be returned by a suitable spring, so that it is in line to be again acted upon by the diverging edge of 77 to again close the shears. The mechanism for raising and lowering the roll 73, by which the 10 direction of the bag is changed, is operated from the sliding rod by a similar mechanism to that previously described for lifting the roll 42.

I have here confined myself to a description of the movements of the cloth and the bag and such portions of the apparatus as it is necessary to describe for a clear understanding of the manner in which the material is advanced from the source of supply to 15 the point where the finished bag is delivered from the machine. I have omitted the description of many of the belts and pulleys, most of which are preferably chain belts running over corresponding sprocket-pulleys, so as to insure a unison in the movement of the parts. It will be manifest that the arrangement of these pulleys for the best operation of the necessary parts is largely a matter of 20 the skill and judgment of the mechanic, as 25 various arrangements of such driving parts 30 may be made, all of which will produce equivalent results.

As the parts which carry the cloth move intermittently and the belts which carry the 35 folded bag to the sewing-machine move continuously, a small space is made between the adjacent bags sufficient for the operation of the twine-cutters.

Having thus described my invention, what 40 I claim as new, and desire to secure by Letters Patent, is—

1. An apparatus for the manufacture of bags comprising mechanism for supplying the material, mechanism for feeding the material 45 intermittently, a cutting mechanism actuated during the intermission of the advance of the material, for severing the material into lengths, means for folding the severed material, a sewing-machine and means for transferring the folded material thereto, a second 50 transferring mechanism operating at right angles with the first-named transferring means, a second sewing-machine for closing the open side of the bag, thread-cutting appliances for 55 severing the thread after the bag passes each sewing-machine, and a single power device connected with the feeding devices, the severing mechanism, the folding devices, and the thread-cutting appliances.

60 2. In a bag-making machine, means for supplying the fabric continuously, means including a reciprocating rack and a pawl-and-ratchet mechanism by which the material is advanced and stopped intermittently, a mechanism 65 for cutting the material into lengths suitable for the bags to be made, means for adjusting the movement of the rack whereby

the advance of the material is varied to suit the size of the bag to be made, and means connected to the rack for operating the cutting 70 mechanism.

3. In a bag-making machine, the combination of means for supplying material continuously, a feed mechanism, means for cutting the material into lengths at each intermission 75 of its forward movement, a reciprocating slide mechanism for operating the feed mechanism, and means connected to said slide mechanism for operating the cutting mechanism.

4. In a bag-making machine, the combination of mechanism for supplying the material, a feed mechanism for the material, means for actuating the feed mechanism, a cutting mechanism for severing the material into lengths, a folding mechanism for the severed 85 portions, a transfer mechanism for the folded portions, stitch-forming mechanism, a horizontally-reciprocating slide mechanism and connections between the same and the cutting and folding mechanisms whereby the said cutting and folding mechanisms are operated by the single reciprocating slide mechanism.

5. The combination of mechanism for supplying the material, a feed mechanism including rollers, a reciprocating rack and pawl-and-ratchet devices, means for regulating the movement of the rack and the consequent advance of the fabric, a cutting mechanism, a horizontal slide mechanism movable with 95 said rack, and connections between said cutting mechanism and the slide mechanism whereby the former is operated by the latter at each intermission of the forward movement of the material.

6. In a bag-making machine, feed-rollers 105 between which the fabric passes, a reciprocating rack at each side of the machine and co-acting devices by which the rollers are intermittently turned to advance the fabric, other feed-rollers between which the material 110 passes, a transversely-operating cutter, slide-rods connected with said racks and means connecting said rods with the cutter and operating the latter on the return movement of the rack whereby the fabric is severed into 115 lengths at each intermission of the forward movement of the fabric.

7. In a bag-making machine, mechanism for advancing the fabric intermittently, a cutting mechanism, a horizontal slide mechanism 120 operated in unison with the mechanism for advancing the fabric, and connections including inclined blocks or plates connected to the slide mechanism and pivoted arms between the blocks or plates and the cutting 125 mechanism, and capable of operating the latter for severing the fabric at each intermission of the forward movement of said fabric.

8. In a bag-making machine, means for supplying the material, mechanism by which the fabric is intermittently advanced, a horizontal slide-rod at each side of the machine and operating in unison with the means for advancing the fabric, a cutting mechanism, a

5 folding mechanism for the severed portions, connections between the slide-rods and the cutting mechanism and other connections between these same rods and the folding mechanism whereby both the cutting and folding mechanisms are operated by a single slide mechanism.

9. In a bag-making machine, mechanism by which the fabric is intermittently advanced, 10 a double set of rollers between which the fabric passes, a cutting device intermediate the two sets of rollers, and mechanism consisting of a reciprocating rod, a fulcrumed lever and an inclined plate carried by said rod adapted 15 to engage said lever whereby the cutting device is actuated.

10. In a bag-making machine, mechanism for advancing the fabric intermittently through the machine, a supporting-belt and 20 rollers over which it passes, said belt serving to support and carry the fabric for the bags, rollers over which said carrying-belt passes whereby its direction is changed to take it temporarily out of the line of travel of the 25 fabric whereby the latter alone is presented between the rollers and a shears between the blades of which the fabric passes at this interval, and mechanism including a slide-rod at each side of the machine, a fulcrumed arm 30 at each end of the movable shear-blade, and devices on the slide-rods to engage said arms and thereby operate said shear-blade by which the shears are actuated to sever the fabric.

35 11. In a bag-making machine, mechanism by which the bag fabric is advanced intermittently through the machine, a supporting-belt upon which the fabric rests, two pairs of rollers between which the fabric passes and 40 by which it is advanced, a direction-roller out of the line of said rollers over which the carrying-belt passes while the fabric passes in a straight line between the two rollers, a stationary and a movable shear-blade between 45 which the fabric passes in moving from one pair of rollers to the other, a slidable rod or rods movable in unison with the movement of the fabric-advancing mechanism, a fulcrumed lever connecting with the movable 50 blade of the shears, an incline carried by the sliding rod adapted to engage the lever on the return movement of the rod and while the fabric is stationary to actuate the shear-blade and sever the fabric, and a spring by which 55 the movable blade is separated from its fellow to allow a further forward movement of the fabric.

12. In a bag-making machine, mechanism for advancing the fabric intermittently, a 60 cutter and a mechanism including a reciprocating slide-rod and connections therefrom for actuating the cutter during the intermission of the forward movement of the fabric whereby the fabric is separated into lengths, 65 rollers between which the separated pieces pass and by which they are advanced from the cutter, folding-rollers situated below the

line of movement of the fabric, a vertically-reciprocating blade by which the severed section is introduced between the rollers and the 70 fabric is folded to the form of a bag, and connections between said slide-rod and the folding-blade whereby the latter is operated.

13. In a bag-making machine, mechanism for feeding the fabric, and moving it intermittently through the machine, mechanism for severing the fabric into lengths, a mechanism for folding the severed sections, consisting of rollers revoluble in contact beneath the horizontal line of travel of the fabric, fulcrumed levers, a folding-blade carried thereby and adapted to press the fold of the fabric section between the folding-rollers, a longitudinally-reciprocating rod, said rod having an inclined surface engaging the lever 85 which carries the folder-blade and operating it during the intermission of the forward movement of the fabric.

14. In a bag-making machine, mechanism for supplying a fabric and advancing it intermittently, mechanism for severing the fabric into lengths sufficient for bags, rollers between which the severed fabric is advanced, a folding device consisting of contact-rollers situated below the line of travel of the fabric, a blade by which the bight of the fabric is pressed down between the rollers, and fulcrumed levers by which the folding-blade is carried, reciprocating rods and inclines carried respectively thereby adapted to engage 95 the levers and actuate the folder during their backward reciprocation, other fulcrumed levers connected with the blade-actuating levers, said second levers carrying the journal-boxes of one of the feed-rollers, and movable 105 in unison with the first movement of the folder so as to raise said roller and release the pressure upon the fabric whereby the latter is left free to be moved by the folder.

15. In a bag-making machine, mechanisms for supplying the fabric, advancing it intermittently and severing it into lengths, a folder consisting of a double set of contact-rollers, and a vertically-movable blade between the two sets of rollers and by which the severed 115 sections of the fabric are pressed between the rollers, a slide-rod and connections for operating the severing mechanism and folding-blade and fulcrumed and spring-pressed levers in which one of the folding-rollers is 120 journaled whereby the roller is allowed to yield for the passage of thickened or creased portions of the fabric.

16. In a bag-making machine, mechanisms for advancing the fabric, cutting it into 125 lengths and folding the severed lengths centrally so as to bring the edges together, a single horizontally-reciprocating mechanism, connections between the same and the cutting mechanism, and other connections between said reciprocating mechanism and the folding mechanism, a carrying belt and tapes between which the folded fabric is delivered and returned to its original plane of travel,

- a sewing-machine disposed with relation to the line of travel of the folded fabric so that one end of the fabric passes through the machine and is sewed together.
- 5 17. In a bag-making machine, mechanisms for supplying the fabric continuously and advancing it intermittently, mechanism for severing the fabric into lengths to form bags, mechanism whereby the fabric is centrally 7c folded to bring the edges together, a sewing-machine through which one end of the folded section is passed and sewed, a thread-cutter, feed-rollers between which the bag-section is received after leaving the thread-cutter, a 15 stop against which the bag is delivered therefrom, a transversely-rotating roller and means for raising it while the bag is being advanced, and afterward depressing it so as to change the direction of motion of the bag, a second 20 sewing-machine through which the edges of the bag are passed and sewed, and a device for cutting the thread before the bag is delivered from the machine.
18. In a machine for making bags, mechanisms for supplying the fabric continuously and advancing it intermittently, mechanism for severing it into lengths for folding it and sewing the end of the folded section, mechanism for changing the direction of motion 25 of the bag at right angles with its first movement, a second sewing mechanism through which the unfinished folded edges are passed to complete the bag, and thread-cutters whereby the thread of each sewing-machine is cut 30 after the bag leaves it, said cutters being actuated in the intervals of the forward movement of the fabric.
19. In a bag-sewing machine, mechanisms for cutting, folding and sewing the bag, a 35 thread-cutting mechanism, longitudinally-reciprocating rods one at each side of the machine, inclined blocks or plates carried by said rods, and operative connections between the cutting mechanism, the folding mechanism and the thread-cutting mechanism operated by said blocks or plates.
20. In a bag-making machine, a mechanism for advancing the fabric intermittently, and mechanism for cutting it into lengths, 40 and for folding said lengths centrally to bring the edges together, a sewing-machine through which one end of the folded section is passed and sewed, a thread-cutter acting after the bag has passed through the machine, a stop 45 against which a partially-finished bag is delivered, a roller having ends journaled in lever-arms, mechanism consisting of slideable rods with inclined blocks or plates adapted to engage the roll-carrying lever-arms whereby 50 the roller is raised to allow the edge of the bag to pass beneath it from the first sewing-machine, and depressed so as to advance the bag at right angles with its former line of travel, and a second sewing-machine through 55 which the unfinished edge of the bag is passed by said movement.
21. The combination in a bag-making machine of mechanism by which a sheet of material is intermittently advanced; a cutter transverse to the line of movement of the material; means for actuating said cutter to sever the material during the intermission of the forward movement; a folder transverse to the line of travel; means by which severed blanks are advanced to the folder; means for actuating the folder; and means for sewing superposed edges of the folded blank. 75
22. The combination in a bag-making machine of mechanism including feed-rolls and mechanism by which a sheet of material is intermittently advanced, a cutter transverse to the line of movement and means by which the cutter is moved to sever the material during the intermission of the forward movement, a folder transverse to the line of travel, 80 means by which the severed material is advanced beneath the folder, means by which the folder is reciprocated and means for uniting superposed edges of the folded blank. 85
23. The combination in a bag-making machine of mechanism including feed-rolls; a transversely-located cutter, and means for operating the same; a transversely-located folder succeeding the cutter, and means for operating the folder; means by which a sheet 90 of material is intermittently advanced, and severed; means by which the severed section is advanced and arrested beneath the folder; continuously-traveling belts to which the folded material is delivered; and sewing 95 mechanisms to which the belts transmit the folded material, to unite superposed edges of the folded material. 100
24. An apparatus for the manufacture of bags, consisting of mechanism by which a sheet of material is intermittently advanced, a transversely-disposed cutter and mechanism actuating it while the material is at rest, a transversely-disposed folding-blade, means for intermittently advancing the severed material until its center is beneath the folder, means for subsequently reciprocating the folder, a continuously-traveling carrier to which the folded material is delivered, and sewing-machines located in the path of its 110 travel whereby the bottom and open side are successively sewed. 115
25. In a bag-sewing machine the combination of feed-rolls and mechanism by which a sheet of material is intermittently advanced, a cutting mechanism next succeeding the feed mechanism and severing a portion of the fabric while the latter still remains in an unfolded condition; and a folding mechanism next succeeding the cutting devices and having a folding-blade arranged transverse to the line of movement of the material, for folding the severed blank across its shortest diameter and sewing mechanism for uniting the superposed edges of the folded material. 120 125
26. In a bag-making machine the combination of means for intermittently advancing a 130

sheet of material, a cutting mechanism, and a folding mechanism said cutting mechanism being interposed between the folding and feeding mechanisms and severing the fabric crosswise into blanks, and said folding mechanism folding said blanks transversely so as to bring the two severed edges together, means for uniting said edges by stitching and independent means for sewing the two parts of

the same finished edge to form the bottom of 10 the bag.

In witness whereof I have hereunto set my hand.

JOHN F. AMES.
